UNITED STATES PATENT OFFICE.

MOSES NEWTON, OF HOLYOKE, MASSACHUSETTS, ASSIGNOR TO THE
NEWTON PAPER COMPANY, OF SAME PLACE.

PAPER FOR PACKING, LINING, AND OTHER PURPOSES.

SPECIFICATION forming part of Letters Patent No. 235,449, dated December 14, 1880.

Application filed November 8, 1880. (No model.)

To all whom it may concern:

Be it known that I, MOSES NEWTON, of Holyoke, in the county of Hampden and State of Massachusetts, have invented certain Improvements in Paper for Packing, Lining, and other Purposes, of which the following is a specification.

My invention relates to paper for packing and lining purposes, designed, by reason of its elasticity, to prevent the fracture of fragile articles surrounded by or enveloped in it, and also to prevent undue wear and give elasticity to carpets or like bodies beneath which it may be placed, the invention consisting in forming or providing the paper with creases, flutes, or corrugations extending in zigzag or irregular lines across its face, in contradistinction to straight parallel corrugations extending in one direction only.

Figure 1 of the accompanying drawings represents a face view, and Fig. 2 a cross-section, of my improved paper.

Paper for packing purposes, for carpet-lining, and similar uses has hitherto been corrugated or fluted, all the corrugations, however, extending in one and the same direction, each parallel with the others.

In the practical use of such paper it has been found that when the paper is subjected to pressure the corrugations flatten out, that the paper is liable also to fold readily or curl up unless held at the edges, and that comparatively little elasticity is secured.

To overcome these difficulties I form the paper, or provide the same after it is formed, with corrugations, flutings, or easy gradual folds arranged in zigzag or irregular lines in such manner that a piece of the paper large enough to include corrugations extending in more than one direction cannot be bent or folded in any direction, except, perhaps, a small space at the corners, without crossing some of the corrugations, whereas the paper having only the straight parallel corrugations may be folded from side to side on the line of the creases or fluting. In other words, the paper having only the straight corrugations extending all in one direction may be flattened out completely by pressure acting in one direction only, and in folding may be doubled along any one of the corrugations without encountering any cross-fold, whereas the paper corrugated in zigzag or irregular lines can

only be flattened out by pressure acting simultaneously in two or more directions, the corrugations in one direction serving to support and stiffen those in another direction. 55

In the drawings, A represents a piece of paper having the corrugations arranged in accordance with my plan. 60

As illustrated in the drawings, the corrugations consist of two elements or parts, a b, each consisting of a short corrugation meeting the other at an angle, the two elements being thus alternated and repeated from one edge of the paper to the other. Instead of meeting at an angle, however, the corrugations may consist, simply, of wavy or curved lines, or the corrugation may be one continuous line arranged in the form of a spiral; or a series of concentric corrugations may be employed. 65 70

The invention consists, broadly, in arranging the corrugations otherwise than in a straight line, and so long as this principle is retained the form or direction of the corrugations may be modified as desired. 75

The use of the paper is not confined to packing purposes or to lining carpets and the like, but may be extended to sheathing and like purposes, and the quality of the paper, its finish, texture, &c., may be varied at will. 80

I am aware that it has been sought to render the paper provided with straight corrugations free from danger of flattening down by placing cotton or other filling in the under sides of the corrugations, retaining it therein by a separate sheet secured to the under side of the first. 85

By my plan I avoid the additional expense of the filling and the retaining sheet, and at the same time provide a superior article. 90

Having described my invention, what I claim is—

1. As an improved article of manufacture, 95 a paper for packing, lining, and similar purposes, provided with corrugations extending in irregular lines, as and for the purpose set forth.

2. The herein-described paper, consisting of 100 the body A, having short corrugations a b formed in its face at an angle to each other.

MOSES NEWTON.
